UNITED STATES PATENT OFFICE.

FRED GRUBER, OF NORFOLK, VIRGINIA.

VALVE MECHANISM.

Application filed January 12, 1921. Serial No. 436,680.

To all whom it may concern:

Be it known that I, FRED GRUBER, a citizen of Germany, residing at Norfolk, county of Norfolk and State of Virginia, have invented certain new and useful Improvements in Valve Mechanism, of which the following is a specification.

This invention relates to improvements in internal combustion engines, particularly in the valve mechanism of such engines for controlling the intake and exhaust of the motive fluid.

It is the principal object of the invention to provide a valve mechanism in which the entire series of valves for an engine of any number of aligned cylinders are mounted transversely disposed to the cylinder block.

A further object of the invention is the provision of a valve mechanism in which the valves are worked by means of plungers which are actuated by the intermediary of a plurality of actuating plates operated by the cam shaft.

Other objects and advantages of my invention will become more fully apparent from the following description, reference being had to the accompanying drawings, and to the appended claim in which the various novel features of the invention are more particularly set forth.

In the drawings,—

Figure 1 is a diagrammatic side view of an internal combustion engine provided with a valve mechanism constructed according to the present invention.

Figure 2 is a top plan view thereof.

Figure 3 is a transverse section on line 3—3 of Figure 2.

Figure 4 is a transverse section on line 4—4 of Figure 2.

Figure 5 is a longitudinal section along line 5—5 of Figure 2.

Figure 6 is a section along line 6—6 of Figure 5, and

Figure 7 is a detail view of the actuating plate system.

Figure 8 is a fragmentary top plan view, partly in section of the valve operating mechanism.

In the drawing, 10 indicates the crank case of a four cylinder combustion engine, and 11 the cylinders thereof. The carburetor is indicated at 12. The connections to the intake manifold are designated at 13 and those to

the exhaust manifold 14 and are contained in a block 15 on top of the cylinder block.

As shown, the crank shaft 16 carries at its outer end the fly wheel 17, and behind the same a bevel gear 18 in mesh with a bevel gear 19 at the end of a shaft or link 20 carrying a bevel gear 21 at its other end in mesh with bevel gear 22 of the cam shaft 23 journaled in a block 24 in the rear of the cylinder block and adapted to operate in the well known manner, the actuating plates 25 hinge- 65
edly secured at their upper ends to a shaft 26 located near the upper end of the block 24 and journaled in the side walls thereof.

As shown in Figure 8 the valves 28 are actuated in pairs by the crank arms of 70
shaft 23.

These plates operate plungers 27 horizontally arranged in block 24 and engaging with their outer free ends the stems 28 of valves 29 of the piston type which enter channels 75
30 in the rear of the block 15, the valves being yieldingly held in closed position by means of coiled compression springs 31 which surround the stems 28 projecting from the rear of block 15 and bear between collars 80
32 on the stems and bushings 33 on the rear face of the block 15. Suitable channels 34 are provided in the block 15 for the reception of the spark plugs.

The intake valves, one of which is shown 85
closed in Fig. 4, will be opened during the intake stroke by the operation of their stems 28 by the cam shaft under compression of springs 31 and the charge will be exploded by the active spark plug in channel 34 to 90
operate the pistons. After the ignition and explosion, the intake valves will be closed by the expansion of their springs 31 as the cam shaft will have ceased to operate the stems 28, while the exhaust valves will then be 95
opened by the operation of their stems by the cam shaft to compress their springs 31 as shown in Fig. 3.

The channels 13' and 14' are provided in the block 15 for allowing a removal of the 100
valves for grinding and cleaning purposes. The channels 13' and 14' are closed by screw plugs 13'' and 14'' respectively.

It will be apparent that by removing the blocks 24 and 15 the entire valve mechanism 105
may be readily lifted from the engine, and that changes may be made in the general arrangement of the parts and construction

22
of the minor details without deviating from the scope and spirit of my invention.

Having thus described my invention, what I claim as new and desire to protect by 5 Letters Patent of the United States is—

In an internal combustion engine, a series of cylinders, a block for said cylinders, a block provided with a series of horizontally disposed channels removably secured on top 10 of said cylinder block, a series of intake and exhaust valves in the channels of said block, the stems of said valves extending beyond the rear face of said block, a third block in

the rear of said first blocks, a plurality of plungers horizontally disposed in said third 15 block, and a shaft longitudinally disposed in said third block, a plurality of actuating plates hingedly secured at their upper ends to said shaft and adapted to be operated by the cam shaft of the engine to operate said 20 plungers for operating said stems and valves.

In testimony whereof I have affixed my signature.

FRED GRUBER.
